(57) **CLAIM**

The ornamental design for a keyboard for a hand held computing device, as shown and described.

DESCRIPTION

FIG. 1 is a top plan view of a keyboard for a hand held computing device;

FIG. 2 is a left, front perspective view thereof; and,

FIG. 3 is a right, front perspective view thereof.

The broken line showing of portions of the handheld computing device is included to illustrate environmental structure and forms no part of the claimed design.

1 Claim, 3 Drawing Sheets

FIG. 1

FIG. 2

FIG. 3
